His Attorney.

UNITED STATES PATENT OFFICE

2,081,830

ELECTRIC CIRCUIT INTERRUPTER

Exra B. Merriam, Swarthmore, Pa., assignor to
General Electric Company, a corporation of
New York

Application January 23, 1936, Serial No. 60,458

3 Claims. (Cl. 200—150)

My invention relates to electric circuit interrupters, more particularly to circuit interrupters of the liquid blast type wherein the arc is subjected to a substantially transverse or cross blast of arc extinguishing liquid during a circuit opening operation, and has for its principal object the provision of an improved circuit interrupter of the aforesaid type.

My invention will be more fully set forth in the following description referring to the accompany drawing, and the features of novelty which characterize my invention will be pointed out with particularity in the claims annexed to and forming a part of this specification.

Referring to the drawing, Fig. 1 is an elevational view, partly in section, of the operative part of an electric circuit breaker embodying my invention; Fig. 2 is a similar view illustrating a modification of the arrangement shown by Fig. 1; Fig. 3 is an elevational view, partly in section, of a double-break type of circuit breaker; and Fig. 4 is likewise an elevational view, partly in section, of another form of double-break circuit breaker embodying my invention.

In certain types of liquid blast circuit interrupters the arc formed upon opening of the circuit is drawn within a pressure confining chamber adjacent to and generally transversely of a pressure relief opening or port. The arc pressure generated within the chamber directs a turbulent blast of arc extinguishing liquid through the relief port, tending to interrupt the arc at that point. Where an appreciable body or head of arc extinguishing liquid, such as insulating oil for example, is directly in the path of the blast, it will be apparent that acceleration of this mass of liquid tends to a certain degree to slow up the application of the arc interrupting blast.

In accordance with my invention, an appreciable part of the aforesaid body of liquid is accelerated in a direction away from the liquid blast upon opening of the circuit by piston structure, or the equivalent thereof. Coincident with the circuit opening movement, the back pressure at the pressure relief or exhaust port is thereby appreciably decreased so that the arc at that point is subjected to the effect of the liquid blast without appreciable delay.

Fig. 1 illustrates a simple way of carrying out my invention in a low-voltage single-break oil circuit breaker. In this case, the circuit breaker casing 1 is provided with an insulating lining 1' and an insulating partition 2 forming an upper low pressure or pressure relief chamber 3 and a

lower pressure confining or arc chamber 4. A movable contact rod 5 extends through the partition 2 and engages at its lower end a fixed socket contact 6 which is mounted in the lower wall of the switch casing. Upon opening the circuit, the rod contact 5 is elevated for separating the contacts. The switch casing 1 contains a suitable arc extinguishing liquid, such as circuit breaker oil, to the level indicated.

The pressure relief passage for the chamber 4 is formed in the present instance by insulating structure 7 forming an annular space or passage, the inner side of which is provided with a circular port 8. This annular passage is in communication at 9 with a pressure relief insulating conduit at 10 formed along the side wall of the circuit breaker casing. As illustrated, the arc drawn between contacts 5 and 6 is centrally of the circular relief port 8 and transversely thereof, so that the arc pressure within the chamber 4 tends to expel oil through the arc radially into the relief port.

For the purpose of appreciably reducing the back pressure at the exhaust port 9 for facilitating the oil blast, a piston 11 is mounted within the passage 10 which forms the cylinder thereof, and is operatively connected to the movable rod contact 5 or switch operating mechanism so as to be raised when the rod contact is raised. The particular arrangement for connecting the piston rod 12 to the movable contact structure forms no part of the present invention and may be as in Fig. 2 wherein the piston moves directly with the rod contact, or as in Fig. 4 wherein the piston is connected through a pivoted lever to the movable contact structure. In this latter case, of course, the relative movement between the movable contact and piston may be as desired.

The piston 11 upon opening of the circuit may initially move a predetermined distance prior to actual separation of the contacts, thereby tending to set in motion, by suction, the oil towards the exhaust passage 9. Furthermore, if the speed of the piston 11 is greatly increased with respect to the contact opening movement, a partial vacuum may momentarily exist within the relief passage upon opening of the circuit, thereby greatly facilitating the oil blast from the chamber 4. This increased speed of application of the oil blast is of considerable importance in interrupting the arc within a few cycles at commercial frequencies.

Fig. 2 illustrates a modified form of Fig. 1 wherein the relief port is simplified and provided

with arc splitting insulating baffles. In this arrangement, the exhaust passage 9 is formed by a tubular extension 13 of the insulating lining terminating adjacent the fixed contact 6 so that the arc is drawn transversely of the passage 9.

An insulating baffle 14 is suitably disposed within the passage 9 transversely of the arc path so that the arc is broken up when driven into the passage 9, the portions of the arc in the passage being acted upon by separate oil blasts. The piston rod 12 is directly connected through a member 12' to the movable rod contact 5 for operating the piston in the manner above described upon opening of the circuit. However, as above pointed out, the connection between the piston 11 and the rod contact may be chosen so as best to anticipate the operating requirements of the breaker.

Fig. 3 illustrates a double-break oil circuit breaker comprising fixed contacts 15 of the well known finger type construction and a movable bridging member 16 connected to a central lift rod 17 for moving the bridging member into and out of engagement with the contacts 15. The fixed contacts 15 are mounted at the lower ends of the lead-in insulating bushings 18 which are suitably mounted in the cover structure (not shown) of the circuit breaker tank. The relatively movable contact structure above described is immersed in an insulating liquid 19, such as oil.

Enclosing the contact structure within the main circuit breaker tank (not shown) is an insulating casing 20 forming a pressure confining chamber and having pressure relief ports 21 opposite the breaks, respectively, formed between the fixed contacts 15 and the bridging member 16. The casing 20 is provided with an upper insulating baffle 22, preferably below the level of the oil 19, for directing the oil blast through the ports 21 when arcing pressure is generated within the chamber.

In this arrangement the oil body in the path of the blast is accelerated by means of a piston 23 operatively connected to the lift rod 17 and operable within an insulating cylinder 24. The cylinder 24 at its lower end is provided with lateral exhaust openings 25 which are generally in alignment with the ports 21. The piston 23 may have a resilient connection with the rod 17 comprising a spring 26 and shoulder 27 for initiating, if desired, movement of the contact structure prior to movement of the oil piston. However, it will be apparent that this arrangement may be reversed, if desired, as in the previous case, depending upon the power of the operating mechanism available and the requirements of the breaker.

In operation, downward or opening movement of the bridging member 16 is accompanied by movement of the piston 23, causing a lateral flow of oil from the cylinder side ports 25 in the direction of the ports 21. The arc pressure within the chamber, assisted by the accelerated body of oil, is therefore more effective to expedite the oil blast and interrupting arcing.

Fig. 4 illustrates an oil circuit breaker of the general type shown by Fig. 3, wherein the oil body exteriorly of the relief ports is accelerated and the back pressure at those ports appreciably reduced as in the case of Figs. 1 and 2. In this case, the circuit breaker tank 33 contains insulating oil 19 in which are immersed the fixed contacts 15 and the movable bridging members 16. The lead-in insulating bushings 18, as in the previous instance, are suitably supported in

the cover of the breaker tank. The bridging member is connected to the conventional lift rod 17 for opening and closing the circuit in the usual manner. Enclosing the contact structure, as in the previous case, is the insulating casing 20 provided with the upper baffle 22 forming the pressure confining or arc chamber. The chamber is provided with lateral relief ports 21 located opposite the two breaks formed upon opening of the circuit.

The relief openings 21 communicate with upwardly extending cylindrical passages 28 opening into the low pressure region above the baffle 22. Operable within the cylindrical passages 28 are pistons 11, the piston rods 12 of which are connected, respectively, to the lift rod 17 through pivoted levers 29, respectively. The levers 29 are pivoted with respect to the circuit breaker structure, as at 30, and are provided with pin and slot connections at 31 and 32 with the pistons 11 and lift rod, respectively. Further description of the operation of the circuit breaker shown in Fig. 4 is believed to be unnecessary other than to point out that the pressure generated within the arc chamber upon opening of the circuit tends to cause a cross blast generally predominating through one or the other of the relief ports 21, this blast being appreciably aided by the reduction of back pressure by the piston operation at the aforesaid ports.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An electric circuit interrupter of the liquid blast type comprising a casing forming a pressure confining chamber, relatively movable contacts operable within said chamber, said chamber containing an arc extinguishing liquid and provided with a pressure relief port, said contacts arranged to draw an arc within said chamber opposite and substantially transversely of said port so that arc pressure in said chamber tends to extinguish the arc by liquid blast through said port, and a piston disposed exteriorly of said chamber operatively connected with respect to the movable contact for reducing by suction the back pressure to said liquid blast at the exhaust side of said port in accordance with the circuit opening operation.

2. An electric circuit interrupter of the liquid blast type comprising a casing forming a pressure confining chamber, said chamber containing an arc extinguishing liquid, relatively movable contact structure operable within said chamber including a pair of fixed contacts and a movable bridging contact arranged to form two breaks in series, said chamber having a pressure relief port substantially opposite each of said breaks, and piston structure disposed exteriorly of said chamber operatively connected with respect to said bridging contact for reducing the pressure in said chamber and accelerating liquid in the direction of said ports and transversely of said breaks in accordance with the circuit opening operation.

3. An electric circuit interrupter of the liquid blast type comprising a casing forming a pressure confining chamber, said chamber containing an arc extinguishing liquid, relatively movable contacts operable within said chamber including a pair of fixed contacts and a movable

bridging contact arranged to form two breaks in series, said chamber having a pressure relief port adjacent and substantially opposite each of said breaks, said ports communicating with a region of comparatively low pressure in said casing, and a piston operable exteriorly of each of said

ports, and means operatively connecting said pistons with respect to said bridging contact for lowering the back pressure by suction at each of said ports in accordance with the circuit opening operation.

EZRA B. MERRIAM.
